HAIR CURLER

William H. Maxwell, Los Angeles, Calif.

Application August 12, 1943, Serial No. 498,341

21 Claims. (Cl. 132—41)

This invention has to do with hair curlers and a general object of the invention is to provide improvements in the construction and formation of such devices and particularly in curlers of the type wherein there is a spindle on which the hair is to be wound, a retainer for use while starting to roll the hair on the spindle, and a fastener to permanently hold the hair after it is wound on the spindle.

This invention has to do with that general class of device which is the subject of my co-pending application Serial No. 498,340, filed on even date herewith.

Curlers of the general type with which this invention relates have, in the past, been made of various materials including metal, molded plastics, and paper or like sheet material. The various constructions heretofore proposed and used have had certain characteristics not altogether satisfactory in practice. For example, metal curlers are heavy, are hard and may be injurious to the hair or to the person of the user. Molded plastic curlers are, generally, hard and rigid having characteristics similar to metal and they are bulky. Paper curlers have possessed certain limiting characteristics, for instance, they have tended to be frail or too flexible, have not had sufficient body at the parts requiring rigidity and have been somewhat inconvenient to handle.

It is a general object of this invention to provide features of construction and formation particularly applicable to curlers formed of sheet material such as paper, fiberboard, sheet plastic, compositions, and the like. The broader features of my invention are applicable, generally to the formation of curlers from sheet material and although it is advantageous to employ a heavy tough paper it is to be understood that I do not thereby wish to limit myself to that particular material as there are features that may be carried out with the use of various sheet materials, even including metal. In general, the features of my invention may be most advantageously carried out entirely with sheet material, and I have by my invention eliminated various difficulties and costs incidental to the formation, assembly, and handling of curlers formed of or including cast parts, wires, springs, etc.

A general object of my invention is to provide a curler of the general type referred to that can be produced from a single sheet of material by automatic machinery, thus eliminating entirely hand operations either in the formation of the parts, in their finish, or in assembly.

5 A general object of the present invention is to provide improvements in the construction and formation of the spindle portion of a curler, which is the basic element of the device, on which the hair is wound. By my invention I provide a spindle of paper which is substantially round in cross section and which may, in practice, be formed by rolling a sheet of material into the desired shape.

10 Another object of my invention is to provide a spindle in a curler of the character described which is formed of light thin material and which is firm and rigid so it can be readily handled or manipulation by the user. In paper curlers formed of sheet material the spindle portion is ordinarily not altogether satisfactory as it has a tendency to be too flexible and to present sharp corners over which the hair may be crimped rather than curled. By my present invention I provide a rounded or curved spindle which gives a true curl to the innermost portions of the hair wound on the device.

15 Another and important object of my invention is to provide a spindle for a curler which is resilient. By my present invention I provide a spindle construction that yields radially as the hair is wound onto it and which exerts a radial pressure outward on the roll of hair, keeping it firm as the hair sets.

20 25 Another object of my invention is to provide effective ventilation in a curler formed of paper. I have provided a spindle of paper which has a longitudinal passage or opening allowing free circulation of air from end to end and having radial openings which allow lateral circulation.

30 35 Another object of the invention is to provide a construction whereby a spindle having characteristics such as I have mentioned may be formed integrally with the other essential parts of the device. It is possible by my invention to provide a spindle with the desirable characteristics mentioned without forming it separately from the other parts of the device.

40 45 Another object of the invention is to provide improvements in the latch or fastening means of a curler. My invention provides a latch arm which is strong and durable and at the same time compact and limited as to size. This is a highly important feature in a curler employing paper as the material for construction.

50 55 Another object of the invention is to provide a fastening means in a curler of the character described involving the combination of an arm designed to overlie the roll of hair on the spindle

and a tab on one of the other parts to cooperate with the arm in holding it in place.

Another object of my invention is to provide an improved retainer in a curler of the character described. By my invention the retaining element may be integral with the other parts and it may be shaped to conform to the hair and thus prevent the formation of sharp bends in the curl.

A further object of the invention is to provide reinforcing means in a curler construction of the character mentioned giving the curler a long life even though it is basically formed of a cheap material generally considered to be weak as compared to materials commonly used in devices of the character mentioned.

Another object of the invention is to provide a general arrangement and combination of parts in a device of the character mentioned facilitating the formation of the entire device as an integral unit. It is a feature of the construction which I have provided that the axis of the retaining arm is at or near the axis of the arm of the fastening means so that the two parts work freely and without in any way interfering with the action of each.

The various objects and features of my invention will be fully understood from the following detailed description of typical preferred forms and applications of my invention, throughout which description reference is made to the accompanying drawings, in which:

Fig. 1 is a perspective view of a curler embodying features of the present invention, showing the device opened out with the retaining arm in position so that the device is ready to receive the end of a strand of hair to be wound on the spindle. Fig. 2 is a plan view of the blank from which the device is formed showing reinforcements added thereto. Fig. 3 is a side elevation of the device showing it in use with a roll of hair in place thereon. Fig. 4 is an enlarged transverse sectional view of the spindle being a view taken as indicated by line 4-4 on Fig. 1. Fig. 5 is a view similar to Fig. 4 showing another form of construction that may be used in the formation of the spindle. Fig. 6 is an enlarged detailed sectional view showing the reinforcement and hinge construction that may be employed in carrying out the invention. Fig. 7 is a view illustrating the manner in which the tab of the fastening means cooperates with the opening in the arm of the fastening means. Fig. 8 is a plan view of the blank for another form of the invention. Fig. 9 is a view similar to Fig. 1 showing another application of the invention, the tab of the fastening means in this case being shown as a continuation of the retainer rather than a continuation of the spindle, as shown in Fig. 1. Fig. 10 is a plan view of a device made from the blank shown in Fig. 8 and illustrating features of construction that may be employed in the arm of the fastening means. Fig. 11 is an enlarged sectional view taken as indicated by line 11-11 on Fig. 10. Fig. 12 is a view similar to Fig. 8 showing a slightly different form of blank. Fig. 13 is a detailed sectional view similar to Fig. 11 showing the construction produced by the blank shown in Fig. 12. Fig. 14 is a view similar to Fig. 9 showing another form of construction and Fig. 15 is a plan view of the blank from which the device shown in Fig. 14 is formed.

Referring in particular to Figs. 1 to 7, inclusive, of the drawings, the device of my invention includes, generally, a spindle 10 on which a strand of hair is to be wound in the form of

a roll H as shown in Fig. 3, a retainer 12 co-operating with the spindle to hold the outer or free end of the strand of hair to the spindle as the rolling operation is started, and a fastening means 13 operable to hold the hair rolled on the spindle.

In general it is a feature of my invention that the various parts of the device are formed of paper, or the like, and preferably of a single sheet of paper, and further that they be formed from a single integral sheet of paper so that the device itself, when finished, is a single integral or continuous unit. By thus forming a curler I eliminate assembly of parts and also hinge pins and like parts which tend to catch or injure the hair.

It is an important feature of the invention that the device in its finished form has a spindle 10 which is substantially round in cross section and has substantial body and rigidity, making it practical and convenient to handle by the user, whereas the other parts of the device retain the characteristic flexibility or softness of the paper out of which the device is formed allowing them to be freely manipulated during the application or removal of the device and so that they do not inconvenience the user while on the head, and are entirely free of danger of injuring or irritating the person of the user.

The body 10, in accordance with the present invention, is curved or rounded so that it is free of corners or edges that may act to give the hair a formation other than a smooth curl. If the spindle is left in the form of a flat strip of paper or like sheet material it may be used so that the end portions of the hair which are the first to be wound onto it are bent over the edges to be crimped rather than smoothly curled. To overcome this I have rounded or curled the spindle 10, giving it a form free of edges or corners. In the embodiment shown in Figs. 4 and 5 of the drawings I curve or curl the body 10 from its original flat form so that it is substantially round and is tubular in form. In the formation of the spindle a flat blank part A is formed as shown in Fig. 2. The side or marginal portions X of the blank part A are rolled inwardly both toward the same side of the blank, so that the finished spindle is substantially round in cross section. In the case shown in Fig. 4 the two side parts X are rolled inwardly and past each other so that the spindle when viewed in cross section has two oppositely inwardly curled side parts which may adjoin or abut each other or which may be spaced somewhat apart, as shown in Fig. 4. The spindle thus formed is substantially round and is essentially a tube open at both ends. The round tubular spindle thus formed presents no edges or sharp parts that could crimp the hair or give the hair other than a smooth curl, and yet the construction is such that as hair is wound onto it the spindle may yield inwardly or radially and as the hair dries the resilience of the material out of which the spindle is formed will keep a slight outward radial pressure on the curl, keeping the hair tight as it dries.

In the form of the invention shown in Fig. 5 the side parts X of the blank A instead of being curled inwardly and down past each other are curled inwardly to overlap each other, forming a substantially round tubular structure. If the parts X are curled to overlap, as shown in Fig. 5, and are merely left in that condition, the spindle has radial resilience or yield substantially the same as that possessed of the form shown

in Fig. 4. If it is desired to provide a rigid unyielding spindle the overlapping parts at Y may be glued or otherwise suitably secured together. It is to be understood that the blank A is proportioned so there is sufficient stock to allow the desired curl or roll to be obtained.

In accordance with my invention I provide vent openings 14 in the spindle 10. These openings may be arranged in any suitable manner throughout the spindle and they may vary in number and in size as circumstances require. In practice it is preferred to form the openings 14 in the blank as it is stamped or initially formed, as shown in Fig. 2. When the spindle is rolled or formed of a blank having openings 14, the finished construction is not only tubular and open at both ends, but has the lateral openings 14 giving free and adequate circulation in all directions.

From the foregoing description it will be apparent that the spindle as thus formed is a substantially round rigid elongate member on which hair can be wound, and that will yield radially and exert a slight radial pressure on the hair as it dries. It will also be apparent that the spindle is formed entirely of a single continuous or integral sheet of material by the simple expedient of forming the blank A and then rolling the edge portions X of the blank.

The retainer 12 is in the form of an arm 11 adapted to overlie the end of a strand of hair engaged on the spindle 10 to hold it during the initial winding of the hair onto the spindle. The retainer is pivotally mounted adjacent the inner end of the spindle 10 and is preferably made about as long as the spindle, as shown in Fig. 1 of the drawings. The retainer 12 is preferably formed so that it has substantial flexibility and to this end it is preferably flat or substantially flat and formed of paper, or the like, such as the paper out of which the spindle is formed. In the preferred construction the retainer 12 may be slightly curved in cross section so that it conforms generally to the curvature of the initial turn of hair around the spindle, thus eliminating any protruding edges that might otherwise tend to cause a kink in the hair. In practice the transverse curvature of the retainer 12 may be very slight and is not such as to give the retainer rigidity which is not desired in this element of the device.

If desired vent openings 70 may be formed in the retainer arm. The openings 70 may be varied in size and arrangement as circumstances require.

The retainer is adapted to have movement relative to the spindle 10 to allow the insertion of the end of a strand of hair between the retainer and the spindle and to clamp over the hair to hold it on the spindle. This movement may be gained through flexibility of the spindle and there may be a definite hinge for the retainer to move about. In the preferred form of the invention there is a hinge or axis 15 about which the retainer 12 may turn and the paper out of which the spindle is formed is sufficiently flexible to allow the spindle to be readily shaped over the hair to be held on the spindle.

In accordance with the broader features of the present invention the retainer 12 may be formed as an independent element and suitably attached to the other parts. However, in the preferred form of the invention it is formed integral with the spindle 10, that is, the spindle and the retainer are formed of a single continuous sheet of

material. In such case the retainer merely projects or continues from the inner end portion of the spindle 10, the sheet of material being bent along the hinge 15 as illustrated in the drawings. The hinge or bend about which the retainer 12 is movable is transverse of the longitudinal axis of the device. When forming the retainer 12 as a longitudinal continuation of the sheet of material out of which the spindle is formed it is preferably cut from the opening provided in the fastening means 13, as will be hereinafter described:

In accordance with the broader principles of the invention the retainer 12 may be formed with or related to the other parts in various manners, an example of which is shown in Figs. 14 and 15. In those figures the retainer 12 is formed integrally with the sheet out of which the spindle is formed but instead of being a longitudinal continuation of the blank A, a tab 16 is formed at the inner end of the sheet out of which the spindle is formed and the retainer 12 is joined with one side or edge of the tab and extends longitudinally of the blank A at one edge thereof. The retainer 12 is arranged in working position by folding it over along the bend line 17 so that its inner end portion overlies the tab 16, as shown in Fig. 14. In this case a hinge 15a may be established by bending the sheet material as indicated in Figs. 14 and 15.

30 The construction shown in Figs. 14 and 15 is merely to make plain the fact that the broader aspects of my invention contemplate various means of joining or connecting the retainer 12 with the other parts, for instance with the spindle 10, and this particular modification is one wherein in an integral construction is provided and wherein in this type of construction is obtained without forming the retainer 12 as a longitudinal continuation of the spindle 10.

40 The fastener 13 serves to hold the roll of hair on the spindle and is generally in the form of an arm 18 projecting from the inner end portion of the spindle 10 and movable about a hinge 19 so that it can be moved from an extended position where it is substantially parallel with the spindle to a position where it overlies the spindle, as shown in Fig. 3. The arm 18 is preferably a flat or substantially flat sheet or length of paper having an opening 20 at its outer end to receive the outer end portion of the spindle 10 or retainer 12.

When the spindle 10 is substantially rigid as hereinabove described and the arm 12 is proportioned just right for the body of hair wound 55 on the spindle, the outer end of the spindle may be engaged in the opening 20 so that the fastener serves to retain the hair on the spindle. However, in practice, such nicety in the relationship of parts seldom occurs or is hard to gain and therefore I provide a tab 21 in connection with the outer end portion of either the spindle 10 or the retainer 12 as a means or element to be connected with the outer end of the arm 18. The tab 21 is preferably adapted to be engaged in the opening 20 of the arm 18.

In the preferred construction the tab 21 is a continuation of the spindle 10 as shown in Figs. 1 and 3 of the drawings. It may, however, be made a continuation of the retainer 12 as shown in Fig. 8 of the drawings. It will be understood that when the hair is wound on the spindle and retainer these two elements are held side by side by the hair and, therefore, the tab 21 can be on either of them. However, in practice, since the

spindle 12 is rigid and a more substantial element of the structure, it is preferred to form the tab on the spindle.

The opening 20 in the outer end portion of the arm 18 is preferably proportioned with relation to the tab 21 so that the parts fit snugly together and thus offer substantial friction to the withdrawal of the tab from the opening after it is once arranged in place therein. To this end I may form the edges 22 of the tab 21 or the edges 23 of the opening 20, or both, so that they are somewhat rough to resist sliding of the tab in the opening. In practice this may be done by providing a torn edge at these parts rather than a cleanly cut edge. Further, in accordance with my invention I may make the tab 21 slightly tapered longitudinally so that its outer end portion 24 is slightly wider than its inner end portion and has a wedging action in the opening 20 as it tends to move outwardly therethrough. A satisfactory gripping action of the tab 21 in the opening 20 may be gained by making the tab 21 slightly wider than the opening 20 so that it will readily enter the opening when turned slightly, as shown in Fig. 7, but fits snugly or tight in the opening when released to move to a normal position in the opening. It is to be understood, of course, that the tab 21 is made sufficiently long to accommodate a wide range of sizes of rolls of hair on the spindle and by being of substantial length the tab 21 forms a dependable and secure fastening means for holding the arm 18 in active position.

In the preferred form of the invention the opening 20 instead of being confined merely to the outer end portion of the arm 18 of the fastener extends or continues throughout the length of the arm 18 to be in the form of a slot therein as shown in the drawings. By this construction the arm 18 is divided into two parts which engage the roll of hair at spaced parts and serve to effectively hold it in place.

In accordance with the broader aspects of the invention the arm 18 may be attached, joined or coupled with the other parts in any suitable manner. It is preferred, however, to form it integrally with the spindle 10 and the retainer 12, in which case the arm 18 is a continuation of the blank A or sheet of material out of which the spindle is formed and out of which the retainer 12 is formed. As shown in Fig. 2 the arm 18 continues from the inner end of the blank A and in this form of the invention the retainer 12 is formed by the strip of material which is removed from the center of the arm 18 by the formation of a longitudinal slot therein. In other words, the retainer 12 is in the form of an elongate arm or tab formed as a result of cutting the slot in the arm 18.

The pivotal axis or the hinge 19 of the arm 18 is preferably located so that it is at or near or coincident with the hinge 15 of the retainer 12 so that these parts can be swung freely without interfering with each other. Such an arrangement of parts is shown in Fig. 1.

In practice the arm 18 of the fastener 13 must have considerable strength and yet it is not desirable to have it be too large. When forming the device of paper if the fastener arm 18 is a single sheet and if it is made to have the desired strength it may be so wide as to be undesirable. By my present invention I may minimize the size of the arm 18 and strengthen it by making it of double thickness. In Fig. 8 I show a blank for forming a curler so that the arm 18 at either

side of the longitudinal opening therein is of double thickness. The blank, as shown in Fig. 8, has parts B provided to form the arm. These parts have a longitudinal fold line 30 so that the material can be folded in over or onto itself as shown in Fig. 11, giving the longitudinal arm parts double thickness. These parts may be merely folded over to remain in place by reason of the crease made in the material, or they may be secured together by means of a suitable adhesive.

It is to be noted that by the construction above described I have provided a latch or fastener arm 18 which is of particularly strong, durable construction and which is compact or of limited lateral extent and which is at the same time sufficiently flexible to allow the arm to operate satisfactorily. I have strengthened or reinforced the arm by making it of double strength without making it rigid so as to interfere with its being bent or formed over a roll of hair as shown in Fig. 3.

In Figs. 12 and 13 I have shown a somewhat different form of construction for making the arm parts of double thickness. In this case the blank parts B' are formed so that the parts which form the margins or edges of the opening cut longitudinally in the arm are folded out so that the opening is made wider than is the case shown in Figs. 8 and 10.

In accordance with my invention I may add suitable reinforcements to the parts hereinabove described to lend strength and life to the device. It will be apparent that the hinges occurring at the parts 15 and 19 may result in ultimate failure at these points. Likewise it will be apparent that the tab 24 is subject to considerable flexure in the course of use and handling of the device. I provide reinforcements for these parts which are subject to wear or excessive flexure.

In the drawings I have shown a reinforcing sheet 30 applied to the sheet of material out of which the other parts are formed in the region of the hinges 15 and 19. The reinforcing sheet 30 may be of any suitable reinforcing material although in practice it is preferred to form it of cloth or a cloth reinforced material which is flexible and at the same time strong and such as to withstand repeated bending. A paper reinforcement will give satisfactory service for most uses. The reinforcing sheet 30 may be glued or otherwise secured in place and it may be shaped and proportioned to have sufficient bearing on or engagement with the other parts, namely the blank A, retainer 12 and fastener arm 18. In manufacture the sheet 12 may be applied to the sheet of stock from which the curler is formed so that the necessary cuts are made in it in the process of manufacturing the curler, or it may be made as a separate tab applied after the curler has been formed.

To reinforce or strengthen the tab 24 I may apply a sheet 40 of reinforcing material similar to that used at 30 to either surface of the tab. The sheet 40 may continue onto the blank A so that the tab is effectively tied thereto.

In using the device, for example, the form of the device shown in Fig. 1, the end portion of the strand of hair to be curled is laid over the spindle 10. The retainer 12 is then engaged over the hair and with the arm 18 extended as shown in Fig. 1 the device is rolled or rotated to wind the hair onto the spindle and around or on the retainer 12. After the first turn or two of the

device the retainer 12 need not be held in position as the hair will hold it.

When the hair is wound onto the spindle the arm 18 of the fastening means is swung over the roll of hair from the position shown in Fig. 1 to that shown in Fig. 3, whereupon the outer end of the spindle is engaged in or coupled with the outer end portion of the arm 18. When a tab 24 is provided as shown in the drawings the tab is inserted through the opening 20 and drawn therethrough to effect the desired fastening or it may be drawn through the opening so that the end portion of the spindle 10 is drawn into the opening 20.

Through the features of construction hereinabove described the fastening means 13 serves to effectively secure the arm 18 in place over the roll of hair until the device is deliberately released.

Having described only typical preferred forms and applications of my invention I do not wish to be limited or restricted to the specific details hereinafter set forth, but wish to reserve to myself any variations or modifications that may appear to those skilled in the art or fall within the scope of the following claims.

Having described my invention, I claim:

1. A hair curler including, a spindle substantially round in cross section, a retainer arm permanently secured at one end of the spindle and adapted to be moved toward the spindle to overlie the spindle and retain hair thereon and comprising a single elongate body, and a fastener arm permanently secured at said end of the spindle and adapted to be swung from a position projecting from the said end of the spindle substantially parallel therewith to a position engaged over a roll of hair on the spindle to hold it thereon and including spaced side parts joined at their outer ends, the arms being of substantially flat sheet material to have flexibility in the direction of their movements.

2. A hair curler including, a spindle substantially round in cross section, a retainer arm secured at said end of the spindle and adapted to be moved toward the spindle to overlie the spindle and retain hair thereon, and a fastener arm secured at said end of the spindle and adapted to be swung from a position projecting from the end of the spindle substantially parallel therewith to a position engaged over a roll of hair on the spindle to hold it thereon, the arms being of substantially flat sheet material to have flexibility of the direction of their movements, the fastener arm having a longitudinal slot formed therein and the retainer arm being formed of the material of the fastener arm removed from the fastener arm by the formation of the slot.

3. A hair curler including, a hollow open ended tubular perforated spindle substantially round in cross section, a retainer arm, means securing said arm at one end of the spindle to be moved toward the spindle to overlie the spindle and retain hair thereon, a fastener arm, means securing the fastener arm at said end of the spindle to be swung from a position projecting from the end of the spindle substantially parallel therewith to a position engaged over a roll of hair on the spindle to hold it thereon, the arms being formed of a single integral sheet of material disposed to lie transverse of their directions of movement.

4. A hair curler including, a hollow tubular spindle substantially round in cross section, a retainer arm secured at one end of the spindle

and adapted to be moved toward the spindle to overlie the spindle and retain hair thereon and comprising a single elongate body, and a fastener arm secured at said end of the spindle and adapted to be swung from a position projecting from the said end of the spindle substantially parallel therewith to a position engaged over a roll of hair on the spindle to hold it thereon and including spaced elongate side parts joined together at their outer ends, the arms being formed of a single integral sheet of material disposed to lie transverse of their directions of movement, the material being folded where the arms are secured.

5. A hair curler including, a hollow tubular open ended spindle substantially round in cross section, a retainer arm secured at one end of the spindle and adapted to be moved toward the spindle to overlie the spindle and retain hair thereon, and a fastener arm secured at said end of the spindle and adapted to be swung from a position projecting from the said end of the spindle substantially parallel therewith to a position engaged over a roll of hair on the spindle to hold it thereon, the arms being formed of a single integral sheet of material disposed to lie transverse of their directions of movement, the material being folded where the arms are secured, the folds being parallel and close to one another.

6. A hair curler including, a hollow tubular spindle substantially round in cross section and open at its ends and having lateral vent openings, a retainer arm permanently secured at one end of the spindle and adapted to be moved toward the spindle to overlie the spindle and retain hair thereon, and a fastener arm permanently secured at the said end of the spindle and adapted to be swung from a position projecting from the end of the spindle substantially parallel therewith to a position engaged over a roll of hair on the spindle to hold it thereon, the arms being of substantially flat sheet material to have flexibility in the direction of their movements.

7. A hair curler including, a hollow tubular spindle open at both ends and substantially round in cross section, being a single piece of sheet material having opposite edge portions rolled in toward each other, a retainer arm secured at one end of the spindle and adapted to be moved toward the spindle to overlie the spindle and retain hair thereon, and a fastener arm secured at the said end of the spindle and adapted to be swung from a position projecting from the end of the spindle substantially parallel therewith to a position engaged over a roll of hair on the spindle to hold it thereon, the arms being of substantially flat sheet material to have flexibility in the direction of their movements.

8. A hair curler having a tubular hair receiving spindle formed of flexible sheet material to be substantially round in cross section and having a substantially fixed longitudinal axis and being split longitudinally to be yieldable radially, a retainer connected to the spindle for holding hair on the spindle, and a fastener for securing a roll of hair on the spindle.

9. A single integral sheet of material having a portion rolled from opposite edges to form a substantially round hollow open ended tubular spindle, a part extending from one end of the spindle forming an arm to retain hair on the spindle, and a part extending from the said end of the spindle to form a fastener arm for holding a roll of hair on the spindle.

10. In a hair curler formed of a single integral

sheet of material of uniform thickness, two portions hinged together at one end of the curler by a fold in the material, one portion being rolled to form a substantially round hollow open ended spindle, the other being a hair retaining arm to overlie the spindle to hold hair thereon, a fastener arm secured at said end of the curler for holding a roll of hair on the spindle, and a tab on one of said portions to cooperate with the fastener arm.

11. A hair curler of the character described including a spindle to receive a roll of hair, a retaining arm connected to the spindle for holding hair on the spindle, and a fastener arm connected to the spindle for holding a roll of hair on the spindle, the fastener arm being formed of sheet material and having portions folded over so that parts of the fastener arm are of double thickness.

12. A hair curler of the character described including a spindle to receive a roll of hair, a retaining arm connected to the spindle for holding hair on the spindle, and a fastener arm connected to the spindle for holding a roll of hair on the spindle, the retainer arm being formed of sheet material and having vent openings therein, the fastener arm being formed of sheet material and having portions folded over so that parts of the fastener arm are of double thickness.

13. A hair curler including three elements permanently joined together, a spindle, a fastener and a retainer, two of the elements being formed of a single sheet of material and being hinged together by a fold in the material, and a body of sheet material secured to said first mentioned sheet of material at the point where it is folded to stiffen and reinforce it.

14. A hair curler formed of sheet material including a part rolled to form an open ended substantially round spindle, said part having vent openings in it, a retainer part connected with one end of the spindle along a transverse line of fold in the material, a fastener arm connected with the said end of the spindle along a transverse line of fold coincidental with the first mentioned line of fold, the fastener arm having an elongate opening left by removal of material to form the retainer part, the portions of the fastener arm at either side of the opening being folded over so those portions are of double thickness, and a tab on the outer end of one of said parts to be engaged in the opening in the fastener arm to hold the arm in place to hold a roll of hair on the spindle.

15. A hair curler including three connected elements, one a spindle to receive hair, one an arm for retaining hair on the spindle and the other an arm for fastening hair on the spindle,

one of the arms being an elongate sheet of material folded lengthwise to have longitudinally disposed portions of double thickness.

16. A hair curler including three connected elements, one a spindle to receive hair, one an arm for retaining hair on the spindle and the other an arm for fastening hair on the spindle, one of the arms being an elongate sheet of material folded lengthwise and in from opposite sides to have longitudinally disposed portions of double thickness.

17. A hair curler including three connected elements, one a spindle to receive hair, one an arm for retaining hair on the spindle and the other an arm for fastening hair on the spindle, one of the arms being an elongate sheet of material with a longitudinally disposed slot and having its side portions folded in to be of double thickness.

18. A hair curler including a spindle on which hair is to be wound, a sheet of material joined to one end of the spindle and including an elongate part forming a fastener to overlie the spindle and fasten hair thereon, said part having longitudinal cuts forming a slot in said part and leaving an arm joined to said part adjacent the spindle and operable to overlie the spindle to retain hair thereon.

19. A hair curler including a spindle on which hair is to be wound, a sheet of material joined to one end of the spindle and including an elongate part forming a fastener to overlie the spindle and fasten hair thereon, said part having longitudinal cuts forming a slot in said part and leaving an arm joined to said part adjacent the spindle and operable to overlie the spindle to retain hair thereon, the portions of said part at the sides of the slot being folded over to be of double thickness.

20. A hair curler comprising a single integral sheet of material having a spindle portion on which hair is to be wound, a fastener arm projecting from one end of the spindle, said arm being longitudinally slotted to form a retainer arm joined to the fastener arm adjacent the spindle.

21. A hair curler comprising a single integral sheet of material having a spindle portion on which hair is to be wound, a fastener arm projecting from one end of the spindle, said arm being longitudinally slotted to form a retainer arm joined to the fastener arm adjacent the spindle, the fastener arm being folded over at opposite sides of the slot to be of double thickness.
